UNITED STATES PATENT OFFICE.

GEORGE CHRISTIAN SMITH, OF GOTTERNBOORG, SWEDEN.

APPARATUS FOR HOISTING AND LOWERING BOATS.

1,310,717.

Specification of Letters Patent. Patented July 22, 1919.

Application filed September 17, 1918. Serial No. 254,492.

To all whom it may concern:

Be it known that I, GEORGE CHRISTIAN SMITH, a subject of the King of Sweden, residing at Gottenborg, in the county of 5 Gottenborg and Bohus and Kingdom of Sweden, have invented new and useful Improvements in Apparatus for Hoisting and Lowering Boats, of which the following is a specification.

10 This invention relates to such davits for ship's lifeboats, which comprises a swinging davit arm arranged to be swung out over the ship's side when in position to launch the boat. More particularly this invention refers to the said class of davits, where the 15 boat is suspended in such a way, that it will be caused to descend into the water by the influence of the gravity, as soon as the swinging davit arm is released from the 20 parts, which secure the arm and the boat in the normal position upon deck, and where the lines, which serve to launch and to hoist the boat, are operated by means of a capstan or a winch. In boat hoisting and lowering 25 apparatus of this class it occurs, that, if the ship stands in an inclined position, the boat on the weather side cannot be swung out freely, because the load set upon the davit arm by the weight of the boat takes in such 30 a direction relative to the inclined davit stanchions, that it prevents the automatical lowering force on the davit arm.

This invention has for its object to remove this objection and to provide means 35 for swinging out the davit arms with the boat even on the weather side of a rather much inclined deck. The invention is characterized by a rope, operated by the ordinary capstan or winch by means of suitable 40 devices and carried over to the boat, where it engages the boat on that side, which, when the boat stands in position, is directed inward to the middle of the ship, whereby the said rope passes over pulleys or blocks in 45 such a way, that, when a pull is set up in the rope by means of the winch or capstan, the rope will cause the boat to be moved outwardly over the ship's side, in consequence causing the davit arms to swing out 50 in position for launching the boat. The parts of the winch or capstan, which operate the rope mentioned, must be connected to the driving shaft of the winch in a detachable manner, so that they can be coupled to or uncoupled from the winch in any arbitrary moments just as wanted, in such

a manner as to prevent the ordinary operation of the winch when launching or hoisting the boat. Further the connection between the boat and the rope in question must 60 also be detachable for the purpose of readily releasing the rope from the boat, when the boat is lowered down into the water.

In the accompanying drawing Figure 1 illustrates an end elevational 65 view of the device, showing the boat on the weather side of an inclined ship with the boat in safe position on deck.

Fig. 2 illustrates the same parts with the boat in position for launching, whereby the 70 boat is shown in two stages of operation, the upper full drawn position indicating the boat ready to be launched and the lower dot-and-dash drawn position, indicating the boat when already lowered a little.

Fig. 3 demonstrates in a decreased scale 75 a deck view, showing the method of arranging the rope and boat lines.

In the drawing the boat is designated with 1, the swinging davit arms with 2, and 3 is 80 the boat supporting line, carried down on to the drums 4 and 5 on the capstan shaft 6, whereby the said lines pass over pulleys or blocks on stanchions 7, which are fixed in a stationary position on the ship's deck 8. 85 A rope or chain 9 is by means of a hook 10 or similar device in a detachable manner attached to a member 17 carried by the inner side of the boat, and this member is so designed, that the hook 10 will easily slip or 90 be slipped from the member as soon as the boat is launched (see the dot-and-dash line figures in Fig. 2). By means of a pulley or block 11 near the ship's side 18 the rope 9 is guided along the deck 8 on to a sheave or 95 drum 12, arranged so as to be temporarily engaged with the capstan shaft 6 by means of a clutch and lever 13 operated by the foot.

The boat supporting lines 3 pass from the drums 4 and 5 respectively to the end of the 100 boat over pulleys or blocks 15, 16.

When launching the boat on the weather side the sheave 12 is by means of the foot operated clutch coupled to the capstan shaft 6, and the capstan is caused to revolve by 105 means of ordinary gears such as a wheel actuated worm gear or similar devices not shown in the drawing. The pull thus set up in the rope 9 will force the boat outwardly, which will be clearly understood 110 when examining the manner, in which the rope 9 is guided from the sheave 12 around

the pulley 11 and to the member 17 on the boat, (see Fig. 1). This outward movement of the boat will cause the davit arms 2 to swing outwardly and downwardly into the position, shown in Fig. 2, as the lines 3 are wound upon their drums 4 and 5 in opposite direction to the rope 9 upon the sheave 12, so that the lines 3 are caused to unwind their drums, when the rope 9 is wound upon its sheave 12.

As soon as the boat has reached the full drawn position in Fig. 2, the clutch 13 is released, whereby the sheave 12 will be disengaged from the shaft 6, and the gravity causes the boat to descend along the ship's side 18. In this moment the hook 10 slips off from the boat 1, and the boat will be launched without obstacle.

Though the invention has been described as illustrated in the drawing, it must be observed, that I do not want to limit myself to this special embodiment, and I wish to be free to vary the single parts in any convenient manner without departing from the spirit and scope of the invention.

Having thus described my said invention, what I claim as new and desire to secure by Letters Patent is:

1. In an apparatus for hoisting and lowering boats, in combination, outwardly and downwardly swinging davit arms, lines operating upon the davit arms, a boat adapted to be suspended from the arms and the lines, operating means with which the lines are connected to operate in one direction, a flexible member operably connected with the operating means but operating thereabout in a direction opposite to the lines, and said flexible member being designed for detachable connection with the boat and arranged so as to swing the arms and boat outwardly upon the actuation of the operating means.

2. In an apparatus for hoisting and lowering boats, in combination, outwardly and downwardly swinging davit arms, lines operating upon the arms, a boat adapted to be suspended from the arms and the lines, operating means with which the lines are connected to operate in one direction, a flexible member, a sheave above which one portion of the flexible member is wound, coacting detachable fastening members on the boat and flexible member, means for temporarily connecting the sheave to the operating means, and the flexible member being arranged to cause an outward swinging of the arms upon the actuation of the operating means.

3. In an apparatus for hoisting and lowering boats, a rotatable shaft, drums rigidly connected thereto, outwardly and downwardly swinging davit arms, lines operating upon the arms and connected to and windable about the drums, a boat adapted to be suspended from the lines and the arms, a sheave loose on the shaft, a flexible member having one portion wound about the sheave, coacting detachable fastening members on the boat and the outer end of the flexible member, means for temporarily connecting the sheave to one of the drums, and the flexible member being trained to a point on the deck of the vessel outside of the mounting point of the arms to cause an outward swinging of the arms upon the actuation of the shaft and during the temporary engagement of the sheave with the drum.

In testimony whereof I have affixed my signature in presence of two witnesses.

GEORGE CHRISTIAN SMITH.
